CLAIM

The ornamental design for the hanging support for multiple rolls of toilet paper, as shown and described.

DESCRIPTION

FIG. 1 is a front elevational view of a hanging support for multiple rolls of toilet paper showing my new design;

FIG. 2 is a rear elevational view thereof;

FIG. 3 is a left side elevational view thereof;

FIG. 4 is a right side elevational view thereof;

FIG. 5 is an enlarged top plan view thereof; and,

FIG. 6 is an enlarged bottom plan view thereof.

The broken line showing of the rolls of toilet paper in FIG. 1 are for illustrative purposes only and form no part of the claimed design.
